Primary Examiner — Michael A. Pratt(74) *Attorney, Agent, or Firm* — Sheridan Ross P.C.(57) **CLAIM**

The ornamental design for a projectile, as shown and described.

DESCRIPTION

FIG. 1 is a perspective view of the projectile;
FIG. 2 is a front elevation view thereof, which is the same as the rear elevation view, top plan view, and bottom plan view;

FIG. 3 is a left elevation view thereof; and,

FIG. 4 is a right elevation view thereof.

The broken lines depict portions of the projectile in which the design is embodied that are not considered part of the claimed design.
